DISPLAY BOX

Allyn C. Beardsell, East Orange, N. J., assignor to
 The Hinde & Dauch Paper Company, Sandusky, Ohio, a corporation of Ohio

Application February 8, 1940, Serial No. 317,842

1 Claim. (Cl. 206—44)

This invention relates to a box for counter display of merchandise, such as canned goods and the like, which combines the capability of being closed for storage or shipment or of being open and, when open, having parts which constitute closing elements arranged to form a raised display back and an easel which inclines the main part of the box. Another feature of the present invention is the disposition of material economically, using two blanks each of which is rectangular in shape with substantially no waste. Further features are positive locking of the parts in display position, and disposition of the parts when in closed position so that all exposed portions are smooth, and all those members which are hinged and turned out when set up are protected against catching on anything when closed.

Other purposes and aims of the invention will be apparent from the following description and from the drawings accompanying it, both of which relate to a preferred embodiment of the invention, it being understood that the invention may be modified within the scope of the claim, without departing from the principles thereof.

In the accompanying drawings

Fig. 1 is a perspective view from front and side of the box open for display;

Fig. 2 is a rear perspective of the same;

Fig. 3 is a perspective showing the box midway between closed and opened position, illustrating the arrangement of the easel;

Fig. 4 is a perspective showing the box closed;

Figs. 5 and 6 are plan views of the blanks from which the box is made, full cuts being indicated by solid lines and creases for folding by dotted lines;

Figs. 7 and 8 are respectively transverse and longitudinal vertical median sections through the set-up box, on planes 7—7 of Fig. 8 and 8—8 of Fig. 7, respectively;

Fig. 9 is a section on plane 9—9 of Fig. 4, looking in the direction of the arrows, and Fig. 10 shows another bottom closing.

The sides, front, and half-laps of my box are made from the blank of Fig. 5, and the back and those bottom and top elements used to set up the display are made from the blank of Fig. 6, the two being secured together along the rear vertical edges 1 and 2 by ordinary box maker's joints, such as stout tape, or otherwise, as may be appropriate.

The box proper, apart from its top and bottom easel features, is composed of back 3, front 4 and side walls 5 and 6, connected at their ends along fold lines shown in Fig. 5 by dotted lines, and

each having along its upper and lower edge a lap panel foldably connected thereto as shown by the dotted lines of Fig. 5. The lap panels are preferably only half-laps, the upper ones being designated as 8, 7 and 9 and the lower as 11, 10 and 12.

The laps 8 and 9 become top laps of the closed box as shown in Fig. 4, while the laps 11 and 12 are preferably folded as inner bottom laps, which places them most conveniently for the purposes of the display arrangement, and are thus shown, although obviously they may be folded as outer bottom laps. If folded as inner bottom laps, they make it unnecessary to empty the contents of the box when changing it from shipping form to display form. The lap 10 forms a part of the bottom, and the lap 7 is an inner wall for the front end, or might of course be put on top of the inner lid when the box is closed for shipment. The top laps 8 and 9 are tucked down as inside walls when the box is set up for display.

The inner top which becomes the display back, is constructed of two panels 15 and 17 as shown in Fig. 6, connected by fold lines 18, 19 which are indicated as dotted in that figure, and separated by a full cut indicated by solid line 16. The panel 15 becomes the display back and the panel 17 its support, Figs. 1 and 2. The cut-out at 16 may be of any ornamental shape desired, a semi-circular arrangement being shown.

Another panel 20 is foldably connected as at 21 to the panel 17. This panel, which forms the easel, is further divided into wings 22 and 23 by fold lines, and by cuts in two steps on each side and extending inward at something of an inclination to the line 21, thus constituting lugs 23 and 25.

When the box is set up for display, the panel 15 is inclined upwards and slightly to the rear, and the panel 17 turned down around the fold lines 18 and 19 to an approximately vertical position. The panel 20 is practically in continuation of the panel 17, but the wings 22 and 23 are turned in and under the box, so that the lugs 24 and 25 fit into holes 26 and 27 made for that purpose in a lap 28, which is foldably attached to the back 3 at the side opposite 15, and which turns under the box, forming the outer bottom when it is set up for display.

Although the box may be closed with the bottom laps 11 and 12 outside, it will be more convenient to close it with the laps 10 and 28 outside, and it is so shown in the drawings. The laps 10 and 28 can thus be held together by tape as at 30, which eliminates the need for

changing the bottom arrangement when setting the box up for display.

To set up the display, the top laps 8 and 9 are thrown back as shown in Fig. 3, and the inner lid is turned up and back. The wings 22 and 23 are turned to bring the lugs 24 and 25 in axial alignment with the length of the box, so that when brought under, in the positions of Figs. 2, 7 and 8 they will register with and go into the slots 26 and 27. The laps 7, 8 and 9 are turned inward, forming inner side walls.

In this way the upper rear end of the box is firmly supported and the entire box placed at an angle, the back panel 15 is raised and is held up by the portion 17, so that it can not move either forward or back. The entire set up position is maintained by the locking action of the lugs 24 and 25 in the slots 26 and 27. By slightly lifting the back of the box, these lugs can be released, and the box again closed by reversing the steps previously mentioned for opening it.

It will be seen from the foregoing that I have invented a container in which the shipping or storing arrangements do not interfere in any way with the display arrangements and the display arrangements are also useful as forming additional top and bottom elements giving the box the necessary double thickness and fully protecting the merchandise. In spite of being so cut and creased as to admit folding into both a display back and an easel, the inner lid also completely covers the merchandise when closed.

It will be understood that variations from the details herein shown may be resorted to, within the scope of the appended claim.

I claim:

A combined shipping and display container comprising in combination two single-wall sides, a double-wall side, two top half-laps, two bottom half-laps, and a bottom partial lap transverse to said bottom half-laps, all the foregoing being made of a unitary blank; and one single-wall side, a full top divided into two panels by a transverse hinge, a tuck hinged to the free end of said full top and a bottom partial lap also transverse to said bottom half-laps, all made of another unitary blank; each of said blanks being of rectangular boundary; said bottom partial laps being hinged to the bottoms of mutually opposed sides, 15 and together forming an outer bottom, said tuck being selectively formable into a supporting easel when said container is in display position, and when formed into such easel comprising a central downward back projection adapted to stand upright and wings hingedly connected thereto 20 along vertical lines for forward swing under the box, said back projection forming a downward continuation of one of the panels of said top, said panel when in easel formation also standing approximately upright behind the box to above the rear end of the box, and being hinged to the other panel of said top, such latter panel in turn being hinged to the top edge of the back wall of the box; said full top of said last-named blank 25 constituting the inner top of the closed container and the top laps of said first-named blank constituting the outer top of the closed container.

ALLYN C. BEARDSELL.
